DESIGN FOR A DRUMSTICK

Arthur W. Geldard, Hartford, Conn.; Aldea
Geldard administratrix of said Arthur W.
Geldard, deceased

Application March 13, 1946, Serial No. 127,401

Term of patent 14 years

(Cl. D56—1)

To all whom it may concern:

Be it known that I, Arthur W. Geldard, a citizen of the United States of America and a resident of the city of Hartford, in the county of Hartford and State of Connecticut, have invented a new, original, and ornamental Design for a Drumstick, of which the following is a specification, reference being had to the accompanying drawing, forming a part thereof.

Fig. 2 is an enlarged cross-section taken through line 2—2 of Fig. 1.

I claim:

The ornamental design for a drumstick, substantially as shown.

ARTHUR W. GELDARD.
